UNITED STATES PATENT OFFICE.

WILLIAM B. SIMPSON, OF HOLDEN, MISSOURI.

ESCAPEMENT-LEVER FOR WATCHES.

SPECIFICATION forming part of Letters Patent No. 337,529, dated March 9, 1886.

Application filed July 13, 1885. Serial No. 171,500. (No modcl.)

To all whom it may concern:

Be it known that I, WILLIAM B. SIMPSON, of Holden, in the county of Johnson and State of Missouri, have invented certain new and useful Improvements in Lever-Escapements for Watches and other Time-Pieces, of which the following is a full, clear, and exact description.

The invention relates to watches, clocks, and other time-pieces in which a lever-escapement is used, and it has for its object the more perfect and easy adjustment of the lever-fork, upon which the accuracy of the time-piece so largely depends.

The invention consists in a novel construction and combination of parts whereby the lever-fork of the escapement can be readily adjusted forward or backward relatively to the ruby-pin of the roller-plate of the movement without taking the watch apart and while the balance-wheel is on, thus enabling a person to make the necessary adjustment while the time-piece is in working order, thereby securing the most perfect accuracy, and this without interfering with the proper perpendicular position of the ruby and fork pins.

Reference is to be had to the accompanying drawings, forming part of this specification, in which similar letters of reference indicate corresponding parts in all the figures.

Figure 1 represents a back view of a watch-movement, in part, having my invention applied; Fig. 2, a transverse section on the line *x x* in Fig. 1; Fig. 3, an outer face view, upon a larger scale, of the adjustable lever fork, showing also the lever pallet; Fig. 4, a section on the line *y y* in Fig. 3, and Fig. 5 a section on the line *z z* in Fig. 3.

A is the lever-fork, and *b* its pin, that engages with the roller-plate *B* on the balance-staff *c*, which carries the balance-wheel *C* of the watch.

D is the lever-pallet, and *d* the staff or arbor which carries it and the lever-fork.

E is the back plate of the "movement."

The lever-fork *A* is made adjustable on or across the face of the lever-pallet toward or from the roller-plate, as required, to correct inaccuracy in the movement, as follows: Said fork is constructed with a longitudinal slot, *e*, through it, extending to opposite sides of the staff *d*, and having either rounded or square

ends. This slot serves to receive in close fit through it on opposite sides of the arbor the shoulders *f* of two screws, *G G*, which engage by their shanks with the lever-pallet *D*, and which serve, by their heads binding on the outer face of the lever-fork, to hold said fork, when adjusted forward or backward, as required, to its place on the lever-pallet and in proper relation to the roller-plate. The shoulders *ff* of said screws serve to keep the lever-fork from shifting laterally both when being adjusted and when adjusted.

In the outer surface of the plate *E* a recess, *g*, is made with two apertures, *h h*, in its bottom, arranged over the heads of the screws *G G*, and of sufficient size to receive a screw-driver through them in all adjustments of the lever-fork to loosen or tighten said screws as required. A thin removable plate, *i*, (shown only in Fig. 2,) may be inserted in the recess *g*, to exclude dust, after the necessary adjustment of the lever-fork has been made.

To adjust the lever-fork *A* as described, the plate *i* is removed, and when the balance-wheel *C* covers, as shown, one of the screws *G* and aperture *h* in the plate *E* over the same said screw is loosened before fitting the balance-wheel to its place, the other or forward screw *G*—that is, the one nearest the roller-plate *B*—being sufficient, or temporarily at least, to hold the lever-fork in position. By loosening said forward screw *G* the lever-fork *A* may then be adjusted forward or backward, as required, to correct any inaccuracy in the "beat" of the movement while the balance-wheel is on and the watch is in working order, and said screw afterward be secured. The balance-wheel may then be taken out of the movement, and the other screw *G* be tightened, and said wheel be subsequently replaced.

Unlike other lever-fork adjustments, it will be seen that there is no necessity to take the watch apart in order to make the adjustment, and such adjustment may be determined with the "balance" on and the time-piece in running order, and such adjustment may be made by almost any unskilled person. Even the temporary removal above referred to of the balance-wheel may be dispensed with when said wheel does not cover the one screw *G*, and there is no liability in making the adjustment to bend or interfere with the proper perpen-

icular position of the ruby and fork pins, and the most accurate adjustment may be made.

If desired, a scale may be arranged on the lever-fork to facilitate the adjustment.

Having thus described my invention, I claim as new and desire to secure by Letters Patent—

1. In lever-escapements of watches and other time-pieces, the lever-fork A, having a longitudinal slot, e, arranged to extend on opposite sides of its staff, substantially as and for the purposes herein set forth.

2. In lever-escapements of watches and other time-pieces, the combination, with the lever-pallet D, of the lever-fork A, having a longitudinal slot, e, the staff d, the perforated

plate E, and the screws G G, whereby the lever-fork may be adjusted forward or backward without taking the watch apart and while the balance-wheel is on, essentially as specified.

3. The combination of the screws G, having shoulders f, with the lever-fork A, slotted to receive said shoulders within it, substantially as and for the purpose herein set forth.

4. The plate E, having a recess, g, and apertures h h in it, in combination with the removable plate i, the screws G G, the slotted lever-fork A, the lever-pallet D, and the staff d, essentially as shown and described.

WILLIAM B. SIMPSON.
